UNIFORM CAP

Harry Lev, Chicago, Ill.

Application January 19, 1949, Serial No. 71,750

9 Claims. (Cl. 2—195)

1

This invention which relates generally to a uniform cap having a frame whereon may be fitted a flexible cover, is concerned more particularly with a distending band or grommet for the cap cover and with the means for attaching the same to an upstanding supporting stay.

The grommet herein disclosed is tubular in cross section and made from a rubber-like material that is both flexible and resilient. Its two ends are coupled to produce an endless band, and for this purpose I may employ a short plug whose opposite end portions are fitted snugly within the hollow proximate end portions of the grommet. To support such an endless grommet at the front of the cap an upstanding stay is used and connected to the grommet by means of fingers which are bent around and clinched upon the grommet in the region of the coupling plug. The gripping fingers of the stay thus serve to support the grommet and, of equal importance, they enhance securement of the ends of the grommet to the coupling plug. This novel means whereby the grommet, plug, and supporting stay are coordinated to perform several functions at once is highly desirable; a strong fastening is thereby produced, and because of its simplicity, dual function, and ease of assembly, such a construction results in great economy together with a much improved uniform cap.

My invention has for its primary object the provision of a novel means of coupling the two ends of a flexible tubular grommet so as to form an endless band and, at the same time and by the same means, connect with an upstanding supporting stay at the front of the cap. A further object is to provide a grommet and stay assembly which is simplified and economical to produce.

Referring to the accompanying drawing:

Figure 1 is a perspective view of a uniform cap of the general type to which my invention applies;

Fig. 2 is a fragmentary central vertical section through the front portion of the cap;

Fig. 3 is a fragmentary perspective view, looking from the front, showing the grommet, the supporting stay, and the holder therefor; and

Fig. 4 which is a fragmentary perspective view, looking from the rear and partly broken away to exhibit certain parts in section, shows the grommet, the coupling plug therein, and the supporting stay.

The present cap may be conventional in that it comprises, in combination, an endless frame F, made desirably of fiber, plastic, or the like,

2

This frame, which optionally may be fabric-covered, furnishes on its inner face a mounting for a holder H in the form of a plate which is transversely bowed and from which tines 10 may be struck outwardly to traverse the frame for clinching upon its outer face. In some such way as this the holder is secured fixedly to the frame.

10 A pair of endwise-bowed bars 11 is also struck out to lie spaced from the holder plate to which they remain connected at their ends. These bars which are disposed inwardly of the holder furnish a mounting for the bowed lower end 12 of an upstanding stay S in the form of a strap 15 which may be slidably fitted to the inside of the bars against the inner face of the plate to extend upwardly of the frame. A stay-holder assembly of this kind is suggested as appropriate in connection with the present invention. The stay in its upper end region is inclined forwardly in accordance with usual practice.

An elongated slot 17 is formed in the upper end region of the stay from whose top is inwardly curved a pair of spaced fingers 18 which are disposed oppositely of the longitudinal center of the stay. The lower finger 19, also curved, is struck inwardly from the stay at the upper end of the slot 17 at a point intermediately of the top fingers. The curvatures of all three fingers are concentric, and together, i. e. one top finger and the lower finger, they extend through an arc of approximately 180°. A tip 20 upstands straight from the lower finger 19, and other tips 21 depend straight from the top fingers 18, all the tips being coplanar. The fingers and tips thus formed and positioned define between them an imaginary opening having a configuration which is substantially D-shaped or half-round.

There is also provided a grommet G which fits within the tip portion of the cap cover C for distension thereof. This grommet which is made from a suitable rubber-like material is both flexible and resilient, and preferably tubular and D-shaped or half-round in cross section. The two ends of the grommet are releasably coupled together so as to provide an endless band, and for this purpose I may employ a plug 22 an inch or two long whose opposite end portions are adapted to be inserted into the hollow ends of the grommet for frictional engagement therewith. Desirably this grommet is of the same material and cross section (internally) as is the tubular grommet itself so as to provide therefor a solid core throughout the region of the coupling. The stay S is secured to the grommet by means

of the fingers 18 and 19 which may be pressed toward the grommet for pressure engagement therewith. The two top fingers 18 then compress the top of the grommet downwardly while clinching it on the inner side at spaced points one near each end of the grommet; while the lower finger in the center upwardly compresses the lower side of the grommet and clinches its inner side at substantially the point of juncture of the grommet ends. All three fingers compress the grommet tightly against the plug 22 so as to securely lock the ends of the grommet together and in addition securely fasten the stay to the grommet.

The means herein disclosed for coupling the grommet ends to each other and to the supporting stay is, of course, applicable to various types of stays, the one herein illustrated and described being chosen by way of example only.

I claim:

1. For use with a uniform cap having a frame whereon may be fitted a flexible cover, an assembly comprising a tubular resilient grommet adapted for reception within the tip portion of the cover for distension thereof, a plug fitted into the meeting end portions of the grommet for frictional connection therewith, a stay upstanding from the frame at the cap front, and vertically spaced means extended from the top portion of the stay in pressure engagement with opposite sides of the grommet at the upper and lower edges thereof.

2. An assembly according to claim 1 in which the grommet has a D-shaped cross section with its flat side inwardly thereof, in which the plug has a similar cross sectional configuration, and in which each of the spaced means in pressure engagement with the grommet is in contact therewith on both its curved and flat sides.

3. An assembly according to claim 1 in which the spaced means in engagement with the grommet comprises three fingers in vertically staggered arrangement, the middle finger contacting the grommet at a point opposite the plug medially thereof.

4. For use with a uniform cap having a frame whereon may be fitted a flexible cover, an assembly comprising a tubular grommet extended substantially through a circle and adapted for reception within the tip portion of the cover for distension thereof, a stay upstanding at the cap front, coupling means at one grommet end in engagement with the opposite end portion of the grommet to establish a frictional connection therebetween, and means extended from the stay in supporting engagement with the grommet and exerting pressure upon the coupling means to augment the frictional connection between the two grommet ends.

5. For use with a uniform cap having a frame whereon may be fitted a flexible cover, an assembly comprising a tubular resilient grommet adapted for reception within the tip portion of the cover for distension thereof, a plug fitted

into the meeting end portions of the grommet for frictional connection therewith, a stay upstanding from the frame at the cap front, and vertically spaced means extended from the top portion of the stay in engagement with opposite sides of the grommet at the upper and lower edges thereof, the spaced means being located at points opposite the plug within the end portions of the grommet and in pressure contact therewith to augment frictional connection between the grommet end portions and the plug engaged thereby.

6. For use with a uniform cap having a frame whereon may be fitted a flexible cover, an assembly comprising a grommet extended substantially through a circle and adapted for reception within the tip portion of the cover for distension thereof, a stay upstanding at the cap front, means connecting together the two ends of the grommet, and fingers extended from the stay in supporting pressure engagement with the grommet.

7. For use with a uniform cap having a frame whereon may be fitted a flexible cover, an assembly comprising a resilient grommet adapted for reception within the tip portion of the cover for distension thereof, a stay upstanding from the frame at the cap front, and vertically spaced means extended from the top portion of the stay in pressure engagement with opposite sides of the grommet at the upper and lower edges thereof.

8. An assembly according to claim 7 in which there is an elongated slot in the stay extending nearly to its top, and in which the spaced means in engagement with the grommet comprises a lower finger struck inwardly from the stay at the upper end of the slot therein and an upper finger extended inwardly from the top of the stay.

9. An assembly according to claim 7 in which there is an elongated slot in the stay extending nearly to its top, and in which the spaced means in engagement with the grommet comprises a lower finger struck inwardly from the stay at the upper end of the slot therein and a pair of spaced upper fingers extended inwardly from the top of the stay and at points which are staggered with respect to the lower finger therebetween.
